UNITED STATES PATENT OFFICE.

GOTTLOB AICHELE, OF NELLINGEN, NEAR ESSLINGEN, GERMANY, ASSIGNOR TO DAIMLER-MOTOREN-GESELLSCHAFT, OF STUTTGART-UNTERTURKHEIM, GERMANY, A CORPORATION OF GERMANY.

TYPEWRITING MACHINE.

Application filed April 6, 1925. Serial No. 21,091.

To all whom it may concern:

Be it known that I, GOTTLB AICHELE, a citizen of the German Republic, and residing at Nellingen, near Esslingen, in the 5 State of Wurttemberg, Germany, have invented certain new and useful Improvements in Typewriting Machines, for which I have filed an application in Germany on January 30, 1924, and of which the following is a specification.

This invention relates to typewriting machines and more particularly to a typewriting machine having a removable paper carrying carriage.

15 One object of the invention is to provide a locking lever engaging with a toothed wheel formed on the axle of the barrel so that the carriage spring located in the barrel is prevented from running down when 20 the carriage is lifted.

A further object of the invention is to provide a locking lever held automatically by the carriage bed plate out of engagement with the toothed wheel of the barrel and 25 adapted when the carriage is lifted off to be brought into the locking position by means of a spring or the like.

The arrangement according to this invention is simpler and more complete than the 30 arrangements normally used.

Means for locking the carriages of typewriting machines, which come into action when the pressure plate carrying the carriage is removed together with the latter from the machine frame are not broadly new. In such arrangements it is however 35 impossible to lock only the barrel which actuates the carriage and to leave the carriage in a removable condition in order to allow of 40 inspection of its operating parts, or for cleaning purposes or the like. In such an arrangement as soon as the fixing devices of the carriage are disconnected, the carriage travels under the influence of the spring until it encounters a guide. If the carriage is removed, the lock is no longer effective and the consequence is that the 45 spring expands within the barrel. In the present invention on the other hand the locking device acts not on the carriage itself, which is removable with the pressure plate, but on its operating means only which is locked in the simplest possible manner.

Manually operated pawls are also known

for locking the barrel but these arrangements as compared with my invention have the disadvantage that their adjustment is always dependent on the operation of the person removing the carriage.

One example of construction of the invention is illustrated in the accompanying drawings in which:—

Figure 1 shows a portion of the carriage of a typewriting machine and the under frame with barrel in part sectional elevation and section, the carriage being lifted off the underframe.

Figure 2 shows the same arrangement but with the difference that the carriage is seated on the under frame.

The carriage *a* as shown in the drawings is formed with a rack bar *b* gearing with a toothed wheel *d* mounted on the barrel *c*. The carriage is always drawn in one direction by the action of the spring as is well known. A pawl *f* is pivotally mounted on the under frame and a pin *g* is loosely connected to the pawl and moves in a guide *h* when the pawl pivots. A spring *k* is located between the head *i* of the pin and the guide *h*. The spring which produces certain pressure, tends to move the pawl in the direction indicated by the arrow and causes the pawl to engage the teeth of the wheel *d* when the carriage is lifted off.

The engagement of the pawl *f* and teeth *d* is therefore automatic and is dependent only on the position of the carriage and frame so that there is no danger of the spring running down.

When the carriage *a* is mounted in position the pin *g* is depressed and the pawl is released from the pinion, the spring *k* being thereby compressed as shown in the drawings.

The invention thus comprises a safety device for locking the spring barrel in typewriting machines, which is automatically engaged and disengaged on the lifting off and replacement of the carriage, so that the spring is always prevented with certainty from running down.

I declare that what I claim is:

In a typewriting machine the combination of an underframe, a bed plate mounted on said frame, a carriage displaceable on but secured to said bed plate, a rack bar mounted on said carriage a toothed barrel mount-

ed on said underframe a spring within said barrel tending to rotate the same, a lever pivotally mounted on said underframe, spring means tending to force said lever to engage with the teeth on said barrel and an abutment connected with said lever and adapted to contact with said bed plate to

cause disengagement of said lever from said teeth when said bed plate is mounted in position on said underframe. 10

In testimony whereof I have affixed my signature.

GOTTLOB AICHELE.
